UNITED STATES PATENT OFFICE.

JOHN H. FLYNN AND THOMAS P. TOLBERT, OF GREENVILLE, SOUTH CAROLINA, SAID
FLYNN ASSIGNOR TO SAID TOLBERT.

VALVE GRINDER.

Application filed October 19, 1923. Serial No. 669,619.

To all whom it may concern:

Be it known that we, JOHN H. FLYNN and THOMAS P. TOLBERT, citizens of the United States, residing at Greenville, in the county of Greenville and State of South Carolina, have invented new and useful Improvements in Valve Grinders, of which the following is a specification.

This invention relates to internal combustion engines and has for its object the provision of an attachment in the nature of an automatic valve grinder which intermittently rotates the valve and its stem as the latter is opened and closed thereby keeping the valve and its seat free from carbon deposits and eliminates the cause and necessity for grinding the valves.

It is also the purpose of the present invention to construct the attachment for the above mentioned purpose which can be installed for use without any material alterations in the valve structure, the only alterations being the provision of a spiral groove in the valve stem, means being provided so that the rotation of the valve and the grinding effect can be dispensed with at any time.

The nature and advantages of the invention will be better understood when the following detailed description is read in connection with the accompanying drawing, the invention residing in the construction, combination and arrangement of parts as claimed.

In the drawing forming part of this application, like numerals of reference indicate similar parts in the several views, and wherein:

Figure 1 is a fragmentary view of an internal combustion engine showing the valve construction and the application of the valve grinder attachment.

Figure 2 is a detail view of the valve.

Figure 3 is a detail view of the body of the attachment.

Referring to the drawing in detail, 10 indicates a valve of the type usually employed in internal combustion engines, and wherein in the stem of the valve is indicated at 11. This stem normally reposes upon the lift rod 13 which operates through a suitable guide 12.

The attachment forming the subject matter of this invention includes a shell or cast-

ing 14 designed to fit over the lift rod guide to which it is secured or fixed relatively by 55 means of a screw or other suitable fastening element 15. This shell is formed with a reduced end portion 16 to closely surround the valve stem 11, being of a diameter to permit of free movement of the valve. An adjustable thumb screw 17 is carried by this reduced end portion and is adapted to be received by a spiral groove 18 formed in the valve stem 11 and of proper length to cause the valve to rotate incident to the opening 60 movement thereof. Consequently, when the valve is opened and closed in the usual manner, it is given a partial rotation so as to provide for a grinding action between the valve and its seat, thereby preventing an 65 accumulation of carbon beneath the valve or around the seat. It is needless to say that under such conditions the motor operates with maximum efficiency, and eliminates the trouble and expense of having the 70 valves ground ever so often. Should it be desired to discontinue the rotation of the valve and the grinding effect at any time, it is only necessary to turn the adjusting screw 75 to remove it out of the spiral groove of the stem and this adjustment can be made in a few seconds. Carried upon the thumb screw 17 is a jam nut 19 which prevents retrograde movement of the screw 17. After the thumb screw 17 has been properly 80 adjusted, the jam nut is screwed tight against the portion 16 of the shell, thus preventing the screw 17 from being loosened by the vibration of the motor, or from any other reason. The nut 19 is preferably provided with flat sides 20 so that a wrench 85 may be used in tightening the same.

While it is believed that from the foregoing description, the nature and advantages of the invention will be readily apparent, I desire to have it understood that I do not limit myself to what is herein shown and described and that such changes may be resorted to when desired as fall within the scope of what is claimed.

Having thus described the invention we claim:

In a device of the class described, the combination with a reciprocating valve stem having a valve thereon, and a valve guide, 105 of a shell designed to fit over the valve

2
guide, means for holding the shell fixed relative to the guide said shell having a reduced portion arranged to surround the valve stem, said stem having a spiral groove, and
5 an adjusting screw carried by the reduced portion of the shell and adapted to be received by said groove whereby rotative

movement is imparted to the valve stem as the latter reciprocates for the purpose specified.

10

In testimony whereof we affix our signatures.

JOHN H. FLYNN.
THOMAS P. TOLBERT.
